18 Claims. (Cl. 57—58.3)

This invention relates to improved mechanisms and methods for plying together a number of strands to form a plied strand and more particularly to mechanisms for plying together a number of strands without appreciably changing the twist of the individual strands.

The invention is applicable to readily flexible strands of substantially any composition or construction and is particularly applicable to strands of cotton, rayon, nylon or other textile materials. All such strands are referred to in this specification and claims simply as "yarns" and it is intended that this term include all filaments or assemblages of filaments or fibers, either natural or manufactured.

In the preparation of yarns for use in the manufacture of automobile tires, industrial belts and in many other instances it is desirable to ply together two or more strands to form a heavier plied strand. This is presently accomplished, in most instances, by a multi-step process wherein the individual strands are given a **Z** twist and then twisted together in **S** twist. Such a process has many well recognized disadvantages. For example, it requires several steps, it requires the rotation of large packages at high speeds, and it requires that the twisted strands be retained under tension for considerable periods of time.

It has been previously suggested that these difficulties could be overcome by plying together the strands of yarn by rotating a balloon of one strand of yarn from a first supply package about a second supply package to thereby twist together the strands from said first supply package and said second supply package. The mechanisms suggested by the prior art for accomplishing this result have, however, met with no considerable degree of commercial success because of, for one reason, the difficulties encountered in obtaining a uniform plying together of the strands.

According to this invention there is provided means, for instance a rotating spindle, for rotating at a substantially constant velocity a balloon of one strand of yarn from a first supply package about a second supply package to thereby twist together the strands from said first supply package and said second supply package at the apex of the balloon, means for retaining the tension in the balloon substantially constant, means for adjusting the tension in the strand of yarn from said second supply package to substantially equal the tension in said strand of yarn in said balloon and means for withdrawing the plied strand under tension at a substantially constant linear rate. While the invention is particularly suitable for plying together two strands, it can be adapted to the plying of three or more strands.

Prior art devices for twisting strands together by rotating a balloon of a strand from a first supply package about a second yarn supply package have resulted in the two strands being brought together in an axial passage of a rapidly rotating spindle. It is a feature of this invention that the strands from the first and second

2

supply packages are brought together for plying at substantially the apex of the balloon and it is this feature that makes possible the novel combination of tension control means to be more particularly described in subsequent paragraphs.

Heretofore the balloon of one strand of yarn has been employed only as a means of rotating a first strand of yarn about a second supply package of yarn to thereby twist the individual strands together and balloon tension has generally not been regulated. It is a novel feature of this invention that means are provided to retain the tension in the strand of yarn in the balloon substantially constant and the constant balloon tension permits this strand to be plied with others employing the balloon tension as a standard.

It is another feature of the invention that the balloon size is retained substantially constant by tension control in the strand in the balloon and the prior art problem of preventing the balloon from growing in size is thereby eliminated.

A further feature of the invention is that it does not require complex metering devices or complex tension equalizing devices.

A still further feature of the invention is that it provides for withdrawing the plied strand at a constant linear rate rather than at a constant tension. This makes possible greatly simplified apparatus and while some prior art devices have had this feature, others have required complex apparatus for withdrawing the plied strand at a variable rate under constant tension.

A feature of one embodiment of the invention is an improved tension equalizing device with no moving parts that does not require damping means and that can be rotated at high velocities without impairing its operating efficiency. Prior art tension equalizing devices generally require moving parts and can therefore not be readily rotated at high velocities without loss of efficiency due to the high frequency vibration and the practical impossibility of obtaining a perfect weight balance in all moving parts on each side of the axis of rotation.

Other features and advantages of the invention, as well as details of construction of several preferred embodiments, will become apparent from the following description when read in connection with the accompanying drawings in which:

Figure 1 is a side elevation, with parts broken away and in section, of a device suitable for plying together two strands of yarn.

Figure 2 is an enlarged elevational view, with parts broken away and in section, of a selected portion of a device substantially identical in most respects to that illustrated in Figure 1 but employing a modified arrangement of yarn guides.

Figure 3 is also an enlarged elevational partial view, with parts broken away and in section, of a selected portion of a device substantially identical to that illustrated in Figure 1 but employing a revolving flyer in place of a single pig-tail guide to bring the two strands together.

Figure 4 is a side elevational with parts broken away and in section of a modified form of the invention employing a novel yarn tension equalizing device adapted to equalize the tension of two strands of yarn being plied into one.

Figure 5 is an enlarged view in perspective of the new yarn tension equalizing device employed in the mechanism illustrated in Figure 4.

With particular reference to Figure 1 of the drawings, the reference numeral 10 represents a stationary shaft mounted through a suitable orifice in a support member 11, the shaft 10 being retained in position by a

bolster 12, lock-nuts 13 and 14, and spring 15. The spring 15 gives a certain degree of resiliency to the mounting. A tubular spindle 16 is journaled about the shaft 1 on antifriction bearings such as the ball bearings 17 and 18 and is adapted for rotation by contact of a whorl portion with a drive belt 19.

The upper end of the spindle 16 has an upstanding extension 20 adapted to receive a ball bearing 21 which, in turn, is adapted to carry a support platform 22. Mounted on the support platform 22 is a yarn supply package support pin 23 adapted to hold a yarn supply package such as cylindrical bobbin 24 carrying a supply of yarn 25. The support platform 22 is prevented from rotating with the spindle 16 by any suitable means such as for instance mounting the entire device at an angle to the vertical and placing a weight 26 eccentrically on the platform 22 so that the platform is prevented by gravity from rotating.

Mounted below the shaft 10 on a suitable support member 27 is a pig-tail guide 28 having its eye 29 substantially in axial alignment with the shaft 10. Mounted between the pigtail guide 28 and the shaft 10 substantially in axial alignment with the shaft 10 is an automatic tension control device indicated generally by the reference numeral 30. As the precise construction of this automatic tension control does not constitute a part of the present invention it is illustrated only schematically as having a number of fixed bars 31 and a number of movable bars 32 through which a strand of yarn 33 from a yarn supply package 34 may be threaded. The tension control device 30 may be and preferably is the type disclosed in my copending application Serial Number 132,226, filed December 10, 1949, now U.S. Patent No. 2,738,141, to which reference may be had for details of construction.

Rigidly mounted on spindle 16 immediately below the support platform 22 is a yarn storage device 35 adapted to receive a strand of yarn passed through an axial passage 36 in shaft 10, an axial passage 37 in spindle 16 and through an orifice 38 in the wall of spindle 16. The yarn storage device 35 is preferably of an eccentric two-step design of the type disclosed and claimed in my copending application Serial Number 244,812, filed September 1, 1951, now U.S. Patent No. 2,811,013, reference to which may be had for details of construction. The eccentric two-step type of yarn storage device is advantageous in that it may be more readily employed with a wide range of sizes and types of yarn, results in a more stable balloon, and is capable of holding up to one and one-half turns of yarn.

Mounted on shaft 16 immediately above yarn storage device 35 and below support platform 22 is a flyer 39, preferably of the disk type, adapted to assist in shaping and controlling a balloon 40 of a strand of yarn extending from the yarn storage device 35 to the eye 41 of a pig-tail guide 42 mounted on a suitable support 43. The pig-tail guide 42 is provided with a pivot 44 so that it may be turned from operative position when the mechanism is not in operation.

Mounted on the support platform 22, for example by pressed fit into an orifice in weight 26, is a pig-tail guide 45 having an eye 46 positioned above the bobbin 24 and substantially in axial alignment with spindle 16. An adjustable automatic yarn tension control device 47 is positioned immediately above the eye 46 of the pig-tail guide 45 and is secured in position by rod 48 press-fitted into a larger cylindrical member 49 which in turn is attached for instance by welding to support platform 22. The particular construction of the automatic tension control device 47 likewise does not constitute a part of this invention and it is indicated only schematically as having a number of fixed pins 50 and movable pins 51 through which a strand of yarn 52 from yarn supply package 25 is adapted to be passed. This automatic tension control device may also be and preferably is of the

type disclosed in my above-mentioned copending application Serial Number 132,226, now U.S. Patent No. 2,738,141.

So that the balloon 40 will not become ensnared in the tension control device 47 or the other members supported by the support platform 22, there is provided a cover 53 mounted on the support platform 22 and having substantially the same shape as the balloon 40. The cover 53 is preferably made of transparent plastic material so that the operation of the members on the support platform 22 can be observed. The lower peripheral rim of the cover 53 is adapted to sit in a groove 54 on the peripheral edge of the support platform 22 so that the cover may be lifted for access to the devices carried by the support platform. The cover 53 is also provided with an orifice 55 at its apex through which strand 52, after passing through tension control device 47, may be passed.

There is indicated by the reference numeral 56 a conventional traverse bar which provides means for evenly winding the plied yarn 57 on bobbin 58. The bobbin 58, employed for the purpose of collecting the plied yarn, is driven by contact of the yarn surface 59 on the bobbin 58 with a drive roll 60 which is rotated at a constant velocity by any suitable means. As will be apparent to those skilled in the art, this insures that the plied strand 57 will be withdrawn at a constant linear rate.

To place the mechanism illustrated in Figure 1 in operation, a yarn end 33 from the yarn supply package 34 is twisted about one end of a semiflexible threading tube, commonly referred to as a "snake." The strand of yarn 33 from the package 34 is then led through the eye 29 of the pig-tail guide 28 and then threaded through the members of the automatic tension control device 30. The snake is then passed into the lower end of the shaft 10 through the passage 36 and into the passage 37 in spindle 16. On striking the upper end of the passage 37 the snake is forced through the orifice 38 and as the snake is pulled through, the strand is threaded into the proper flow path. The strand is then led to the outer peripheral edge of the disc flyer 39 and then through the eye 41 of the pig-tail guide 42. The strand is then passed over traverse bar 56 and wrapped a few turns around the spool 58.

When placing the device in operation for the first time it will generally be advantageous at this point to make a rough adjustment of the automatic tension control device 30. This can be done by moving the spindle 16 into operative position against belt 19 so that the spindle is rotated at a high velocity. The spool 58 is then lowered against roll 60 and the tension control device 30 adjusted to give a balloon of approximately the desired size. The spool 58 is then removed from contact with roll 60 and rotation of the spindle is stopped. If the mechanism has been in previous operation with strands of substantially the same type, the tension in the strand emerging from the spindle 16 will generally be close enough to the correct value to make adjustment at this time unnecessary.

After the first strand 33 has been threaded through the mechanism and an approximate adjustment of tension has been made, the pig-tail guide 42 is turned on pivot 44 so that the cover 53 can be removed from operative position. A yarn end 52 from supply package 25 is then threaded through the eye 46 of pig-tail guide 45 and then through the automatic tension control device 47. A rough adjustment should be made at this point so that the tension necessary to pull the strand from supply package 25 through the eye 46 and the tension control means 47 is approximately the same as that required to pull the first strand 33 through its proper flow path. The yarn end from the supply package 25 is then threaded through orifice 55 in cover 53, and then through the eye 41 of pig-tail guide 42. The cover 53 is then replaced and

pig-tail guide 42 lowered into operative position. The yarn end from supply package 25 is then led over the traverse bar 56 and given a few turns around spool 58 alongside the first strand. The device should then be placed in operation and automatic tension control 30 adjusted to give a proper size balloon with the least amount of flutter.

If an evenly plied strand is desired, it is necessary that the tension in the strand 52 exactly equal the tension in the strand 33 since otherwise the strand with the lesser tension will be wrapped around the other with the strand having the greater tension forming a core. While it is a feature of this invention that the tension in strands 33 and 52 will remain equal once so adjusted, it is first necessary to equalize the tension in strands 33 and 52 as they enter the eye 41 and this is preferably accomplished primarily by trial and error adjustment of the tension control device 47. The reasons for this will be more fully explained in subsequent paragraphs.

The yarn storage device 35 when employed in the manner contemplated in this invention not only drives the balloon 40 but also serves as a non-adjustable automatic tension control responsive to variations of tension in the strand 33 as it emerges from the orifice 38 and also responsive to variations in the size of the balloon 40 to thereby control the size of the balloon. As will be understood by those skilled in the art, if the size of the balloon is retained constant, the tension in the yarn comprising the balloon also remains constant. For example, if the input tension in strand 33 should decrease without being properly regulated by the automatic tension control 30 the balloon will tend to increase in size thereby causing more air drag and a resulting increase of wrap around on the yarn storage device. The increase in warp around is accompanied by a corresponding increase in tension, which tends to bring the balloon back to the original size. In view of this it will be apparent that the primary purpose of the automatic tension control means 30 is to retain the tension in the strand of yarn 33 as it emerges from the orifice 38 within the best limits capable of being handled by the yarn storage device 35 and that it is impossible to greatly change the tension in the yarn of the balloon 40 by adjustment of the tension control means 30 when the apparatus is operating properly. In other words, if one attempts to obtain an appreciably larger balloon by lessening the tension on strand 33 by adjustment of the tension control means 30, the yarn storage device 35 will substantially correct for the decreased tension by increased wrap around and retain the balloon size substantially constant.

In view of the above, it will be apparent that the primary method of equalizing the tension in strands 52 and 33 as they enter pig-tail guide 41 is by adjustment of the variable tension control means 47. This may be readily accomplished by trial and error since it is apparent from observation of the plied strand 57 whether or not the tensions in strands 52 and 33 are equal and if they are not, in which the tension is greater. If for example it is observed that the strand 52 is serving as a core in the plied strand 57 and that strand 33 is simply being wrapped around strand 52, it is apparent that the tension in strand 52 is too high and should be decreased. This is accomplished by removing the spindle 16 from contact with the belt 19 to stop its rotation, raising the cover 53 and making the proper adjustments on automatic tension control device 47. The cover 53 is then lowered into operative position and operation of the device again initiated, making further adjustments if necessary. Once the tensions in the two strands are properly adjusted, they will remain so since, as previously explained, the tension in the balloon is retained at a constant value by the yarn storage device 35, and the tension control device 47

automatically retains a tension in strand 52 equal to the value to which it is originally adjusted.

Although tension equalization is primarily accomplished by adjusting the tension in strand 52, small adjustments can also be made in the tension in strand 33 by raising or lowering the pig-tail guide 42 to change balloon size and thereafter making a corresponding adjustment in tension control 30. In fact, small changes in the tension in strand 33 can be made simply by adjustment of the tension control 30 if an eccentric two-step yarn storage device is employed. This is possible because of the eccentric design of the yarn storage device which, while having many advantages, results in slight differences in balloon size for very large differences in wrap around. However, adjustment of the tension control 30 to obtain tension equalization is generally not advantageous since, with a given size and type of yarn, there is an optimum range of wrap around for maximum balloon stability and tension control 30 is preferably employed only to insure that wrap around in the yarn storage device 35 is within the optimum range. As previously indicated, this is accomplished by adjusting tension control 30 to give a balloon with the smallest amount of flutter. Once the wrap around in the yarn storage device 35 is adjusted to be within the optimum range, the fluctuations in the tension in the yarn entering the yarn storage device are generally of such small magnitude that the device operates at near maximum efficiency at all times.

When the tensions in the individual strands 52 and 33 are equal, the strands are evenly displaced one by the other resulting in the plied strand 57 consisting of two evenly interlayered helices of yarn having substantially the same twist in the individual strands as was originally present except for that imparted by removal of the strands from the yarn supply packages. Further, since the balloon rotates at a substantially constant velocity, thereby resulting in a constant number of turns of the two strands 33 and 52 one about the other in a given period of time, and since the plied strand 57 is withdrawn under tension at a constant linear velocity as previously explained, it will be apparent to those skilled in the art that not only is the plied strand 57 uniform with respect to the displacement of one strand by the other but that in the plied yarn the two strands are twisted about each other a constant number of times per unit length. In other words this invention makes possible a plied yarn completely uniform in every respect.

In Figure 2 of the drawings there is partially illustrated 50 a modified form of the invention wherein a strand of yarn 61 from a yarn supply source on a stationary platform, not illustrated, is passed through an automatic tension control device 62 and out a passageway at the apex of a cover 63 to be plied together with a second strand 64 55 being rotated in the form of a balloon. The device in Figure 2 differs from that in Figure 1 in that the simple orifice 55 and the pig-tail 42 in Figure 1 have been replaced respectively with a low friction trumpet generally indicated at 65 and a forming trumpet generally indicated at 66. The modification of Figure 2 is especially adapted 60 for winding highly plied yarns wherein the apex of the balloon may tend to ride down the plied strand 67 until it is bearing on the plastic cover. The advantages of the modification in Figure 2 in this regard will be made clear 65 in the following discussion.

Referring to Figure 2 in greater detail, a tubular member 68 is rigidly affixed in a suitable orifice in the upper extremity of the cover 63 which is mounted on a stationary support platform, not illustrated. Journaled in the 70 member 68 is a yarn trumpet 69 which is freely rotatable by virtue of low friction bearings such as ball bearings illustrated at 70 and 71. The trumpet 69 has an axial passageway 72 adapted to receive the strand of yarn 61 and upper lip 73 designed to present a smooth surface for the strand 64 should it be forced down upon the trumpet

by the high twist in the plied strand 67. The lip 73 is also designed so that the angle of strand 64 with respect to the plied strand 67 will somewhat approximate the angle of the strand 61 with respect to the plied yarn 67 thereby insuring a proper plying together of the two strands when the tensions therein are equal.

With further reference to Figure 2, a movable block 74 is resiliently pressed against a fixed block 75 by means of spring 76 mounted around a pin 77 permanently affixed to the block 74 for example by pressed fit into a suitable opening. Matching grooves are machined in blocks 74 and 75 so that when pressed together there is formed a circular passage 78 suitable for receiving the plied strand of yarn 67. One end of the pin 77 is slidably positioned in a passageway 79 in block 80 so that the pin 77 cooperates with the spring 76 in holding the block 74 in operative position. The block 79 controls the tension exerted on spring 76 and is adjustably mounted on a suitable support, not illustrated.

The operation of the modification illustrated in Figure 2 is substantially identical to that of the device illustrated in Figure 1. The strand 61 from a yarn supply package on a stationary platform, not illustrated, is threaded through the tension control device 62, through the axial passage 72 of trumpet 69 and then through the passage 78 in trumpet 66. The strand 64 is threaded through a hollow spindle, around a yarn storage device and a flyer as in the device illustrated in Figure 1 and then through passage 78 in trumpet 66. Both strands are then passed to a spool, not illustrated, adapted to withdraw the plied yarn under tension at a constant linear velocity.

When the device is placed in operation, should the apex of the balloon move downward to the position illustrated in Figure 2 of the drawings, the low friction trumpet 65 is rotated to result in the strands 61 and 64 being subjected to a minimum of attrition and at the same time result in the strands being brought together at a more desirable angle. On being brought together at the apex of the balloon, the individual strands 61 and 64 are twisted together to form a plied strand 67 which then passes into the passageway 78 of the forming trumpet 66. The pressure of the blocks 74 and 75 on the twisted strand further smooths out irregularities and makes the yarn more uniform. Should a knot appear in the twisted strand 67 below the trumpet 66, the resilient mounting of the block 74 allows the knot to pass without breakage of the strand.

In Figure 3 of the drawings there is partially illustrated a modification of the invention substantially identical to the embodiment of Figure 1 except that the pig-tail guide 42 of Figure 1 has been replaced by a more complicated revolving flyer and trumpet. In this embodiment of the invention there is illustrated a shield 81 about which a balloon of yarn is adapted to be rotated by a revolving spindle, not illustrated. A tubular trumpet 82 is mounted in axial alignment with the rotating spindle and is carried by a suitable support 83. The trumpet 82 is adapted for rotation by virtue of bearings 84 and 85 and is retained in position by a nut indicated by the reference numeral 86. Mounted around the trumpet 82 below the support member 83 is a flange member 87 secured for instance by friction fit. The flange member 87 carries two diametrically opposed tubular pins 88 and 89 mounted at right angles to the longitudinal axis of the trumpet 82. Press fitted in the ends of each of the pins 88 and 89 is a wire loop flyer 90 having three smaller loops 91, 92 and 93. The loops 91 and 92 are formed equidistant on either side of the longitudinal axis of the trumpet 83 while the loop 93 is substantially in line with the loops 91 and 92 but considerably further removed from the axis of rotation.

The operation of the modification shown in Figure 3 is substantially identical to that of the embodiment shown in Figure 1. A first strand of yarn 94 is led from the peripheral edge of a disk flyer, not shown, through loop 93, through loop 92, through an axial passage 95 in the

trumpet 82 and then to take-up means, not illustrated. A second strand of yarn 96 is led from the automatic tension control means 97 mounted on the stationary platform, not illustrated, through the orifice 98, through the loop 91, through the axial passage 95 in trumpet 82 and then to the constant take-up means along with the first strand 94. When placed in operation, the balloon of the strand 94 causes the flyer 90 and trumpet 82 to rotate in synchronism with the spindle as a result of the considerable moment of rotation exerted on the flyer 90 by the strand 94 as it passes through the loop 93. The loops 91 and 92 being equidistant from the axis of rotation of the trumpet 82 insure that the two strands 94 and 96 will converge at equal angles with respect to the plied strand 99 thereby assisting in the attainment of uniformity in the plied yarn.

In Figure 4 there is illustrated a device generally similar to that illustrated in Figure 1 but employing a novel tension equalizing device generally indicated by the reference numeral 100 in Figure 4 and illustrated in detail in Figure 5. As will be seen from the drawings the tension equalizing device comprises two rows of elongated elements or pins each row being adapted to receive one strand of yarn immediately prior to the strands being plied together. The tension equalizing device illustrated in the drawings is designed to equalize the tension in only two strands being plied together and therefore has only two rows of pins with the mean plane of each row being at an angle of approximately 180° to the mean plane of the other row. As will be more apparent from the detailed description of the equalizing device to follow, however, the device can be adapted to equalize tension in several strands by providing a row of pins for each of the several strands, the rows being so positioned that the angle between the mean plane of adjacent rows of pins is approximately $360^\circ/n$ wherein n represents the total number of rows.

With particular reference to Figures 4 and 5 of the drawings there is illustrated a rotatable spindle 101 a yarn storage device 102 carried by the spindle 101 and adapted to be rotated therewith, and a disk flyer 103 also carried by the spindle 101 and adapted to be rotated therewith. A stationary platform 104 is carried by the spindle 101 which is free to revolve with respect thereto by virtue of roller or ball bearing 105. The platform is restrained from rotating with the spindle 101 by means of an eccentric weight 106.

The platform 104 carries the cover 107 which is sectioned and adapted to be opened by virtue of hinge 108. When closed the upper section of the cover is retained in position by clip 109. An automatic tension control device of the gate type 110 is mounted within the cover 107 in axial alignment with the rotatable spindle 101 and is supported by the upper section of the cover 107 by means of arm 111 attached to the cover by any suitable means such as by cementing.

Mounted in a suitable opening in the apex of the cover 107 is a tubular member 112 and journaled in the tubular member 112 by means of bearings 113 and 114 is a shaft 115 rotatable about the extended axis of spindle 101. The shaft 115 carries two diametrically opposed wire yarn guides 116 and 117 extending at right angles from the longitudinal axis of the shaft 115 and above each of the yarn guides 116 and 117 are two rows of fixed pins 118 and 119 mounted on the shaft 115.

Each of the rows of pins 118 and 119 on the shaft 115 is adapted to receive a strand of yarn passed through the wire guides 116 and 117, the strands being subsequently plied together at a point substantially in axial alignment with the spindle 115. The pins 118 and 119 are preferably mounted at a small angle with respect to the shaft 115 so that they extend at approximately right angles to the strand of yarn which they are adapted to receive.

As best shown in Figure 5, alternate members of the pins 118 and 119 are disposed at a slight angle for example less than 20° and preferably about 10° with respect

to each other thereby presenting a tortuous path for a strand of yarn threaded between alternate pins. The opposing faces of alternate pins in each row should be rounded to present a smooth surface to the strand of yarn passing thereover and can if desired be chrome plated or the like to increase their resistance to wear. The extremities of alternate pins are curved to form hooks which serve the purpose of retaining the strands in their proper courses at such times as might be necessary.

To prepare the device illustrated in Figure 4 for operation, a strand of yarn 120 is threaded through the passage 121 in spindle 101, through the orifice 122, around the yarn storage device 102 and over the peripheral edge of the flyer 103. The strand 120 is then threaded through the wire guide 116 and between alternate pins 118 and through the eye 123 of a pig-tail guide 124. The strand of yarn 120 is then led to a take-up device adapted to collect the strand at a constant linear velocity. A second strand of yarn 125 from a yarn supply package 126 on package support pin 127 carried by the stationary platform 104 is threaded through the automatic tension control means 110 and then into an axial passage 128 extending part way through the rotatable shaft 115. The strand 125 is then lead through an orifice 129 in the wall of the shaft 115 immediately below the wire guide 117. Strand 125 is then passed through the wire guide 117 and between alternate pins 119 through the eye 123 of the pig-tail guide 124 and then through the yarn take-up device alongside the strand 120.

When the device illustrated in Figure 4 is placed into operation, the strand of yarn 120 forms a balloon rotating about the cover 107 which in turns causes rotation of the shaft 115 which results in the strands 120 and 125 being twisted together below the eye 123 of the pig-tail guide 124 and immediately above the tension equalizing device generally indicated at 100. As previously explained, the tension in the strand of yarn 120 while in the balloon is retained substantially constant by the yarn storage device 102 so that it is supplied to the wire guide 116 at a constant tension. The automatic tension control device 110 should then be adjusted to supply the strand 125 to the wire guide 117 at substantially the same tension at which strand 120 is supplied to wire guide 116.

The operation of the automatic tension equalizing device illustrated in Figures 4 and 5 will now be explained. If the tension in strand 120 as it enters guide 116 is greater than the tension in strand 125 as it enters guide 117, the apex of the balloon, indicated at A where the two strands are being twisted together, will be pulled in the direction of the strand 120, as indicated by the dotted line, and will thereby be positioned so that the apex may be represented at A'. This results in the strand 125 being moved laterally toward the spindle 115 thereby increasing the contact of the strand 125 with the pins 119 and causing the strand 125 to follow a more tortuous path. At the same time the strand 120 is caused to move laterally away from the spindle 115 thereby decreasing the contact of the strand 125 with the pins 118 and causing the strand to follow a less tortuous path. As can be seen, this results in the tension in the strand 125 as it meets strand 120 being increased to where it is substantially equal to the tension in strand 120 at the point of contact. It will also be seen that the tension equalizing device results in the two strands being brought together at approximately the same angle with respect to the plied strand thereby resulting in still greater uniformity in the plied strand.

It should be emphasized that the tension equalizing device operates most efficiently for small differences in tension in the individual strands and that if the difference in tension becomes too great, tensions in the individual strands will not be equalized to a sufficient extent to result in a uniformly plied strand. If therefore when the device of Figure 4 is placed in operation it is noticed that the apex A' of the balloon continues to describe a circle of appreciable diameter it is an indication that tension

in strand 125 at wire guide 117 is not substantially equal to that in strand 120 at wire guide 116. The device should therefore be stopped and the automatic tension control means 110 adjusted to supply the strands to the tension equalizing device at a more nearly equal tension. When the device is operating properly, the apex of the balloon will remain in substantially axial alignment with the rotating shaft 115 with only occasional small movements to one side or the other.

Having thus described my invention what I claim and desire to protect by Letters Patent is:

I claim:

1. A mechanism for plying together strands of yarn, said mechanism comprising in combination means adapted to rotate, at a substantially constant velocity, a balloon of a strand of yarn from a first supply package about a second yarn supply package, tension control means adapted to retain the tension in said strand of yarn in said balloon substantially constant, adjustable tension control means adapted to supply a strand of yarn from said second yarn supply package at a uniform tension substantially equal to the tension in said strand of yarn in said balloon, guide means adapted to bring together, at substantially the apex of said balloon, said strand of yarn from said second yarn supply package and said strand of yarn in said balloon, whereby the strands are plied together, and means adapted to withdraw the plied strand of yarn at a substantially constant linear rate, said guide means comprising a forming trumpet adapted to smooth out irregularities in the plied strand.

2. The apparatus of claim 1 wherein there is employed, in combination with said forming trumpet, a rotatable low-friction trumpet adapted to bring the strands together with a minimum of attrition and at a more nearly equal angle with respect to the plied strand to thereby improve the uniformity of the plied strand and the lay of the individual strands in the plied strand.

3. A mechanism for plying together strands of yarn, said mechanism comprising in combination means adapted to rotate, at a substantially constant velocity, a balloon of a strand of yarn from a first supply package about a second yarn supply package, tension control means adapted to retain the tension in said strand of yarn in said balloon substantially constant, adjustable tension control means adapted to supply a strand of yarn from said second yarn supply package at a uniform tension substantially equal to the tension in said strand of yarn in said balloon, guide means adapted to bring together, at substantially the apex of said balloon, said strand of yarn from said second yarn supply package and said strand of yarn in said balloon, whereby the strands are plied together, and means adapted to withdraw the plied strand of yarn at a substantially constant linear rate, said guide means comprising a rotatable trumpet carrying a flyer adapted to bring the individual strands together at approximately an equal angle with respect to the plied strand.

4. A mechanism for plying together strands of yarn, said mechanism comprising in combination a stationary shaft having an axial passage adapted to receive a first strand of yarn, adjustable automatic tension control means adapted to feed said first strand of yarn into said axial passage at a substantially constant tension, a rotatable spindle adapted to rotate about said shaft, said spindle having an orifice in the wall thereof adapted for passage of said first strand of yarn, a support platform carried by said spindle and rotatably mounted thereon, means for preventing rotation of said platform with said spindle, a yarn supply package support pin mounted on said platform, adjustable automatic tension-responsive feed-back yarn tension control means carried by said spindle and adapted to control and maintain substantially constant the tension in a second strand of yarn emanating from a supply of yarn on said support pin,

a disk flyer mounted on said spindle and adapted to assist in the control of a balloon of said first strand of yarn rotated about said support platform and the structures supported thereby, automatic tension control means adapted to be responsive to slight variations of tension in said first strand of yarn issuing from said orifice and also to variations in the size of said balloon to thereby control and maintain substantially constant the tension in the yarn in said balloon, guide means adapted to guide together said first strand and said second strand of yarn at substantially the apex of said balloon thereby resulting in said first strand and said second strand of yarn being twisted together to form a single plied strand, means adapted to withdraw said plied strand under tension at a substantially constant linear rate, and an adjustable tension control device adapted to supply a strand of yarn to said axial passage in said shaft at a substantially constant tension, said guide means comprises a rotatable tension equalizing device adapted to substantially eliminate small differences in the tensions in the strands immediately prior to their being plied together.

5. A mechanism for plying together strands of yarn said mechanism comprising in combination means adapted to rotate, at a substantially constant velocity, a balloon of a strand of yarn from a first supply package about a second yarn supply package, tension control means adapted to retain the tension in said strand of yarn in said balloon substantially constant, adjustable tension control means adapted to supply a strand of yarn from said second yarn supply package at a uniform tension substantially equal to the tension in said strand of yarn in said balloon, tension equalizing guide means adapted to bring together, at substantially the apex of said balloon, said strand of yarn from said second yarn supply package and said strand of yarn in said balloon, whereby the strands are plied together, and means adapted to withdraw the plied strand of yarn at a substantially constant linear rate, said tension equalizing guide means comprising an elongated support member and a plurality of rows of fixed pins, the pins in each of said rows being so disposed that the axes of alternating pins extend in planes diverging through a small angle less than about 20° , the mean plane of each row of pins being substantially radial to the longitudinal axis of said support member and the angle between the mean planes of adjacent rows of pins being approximately $360^\circ/n$ wherein n represents the total number of rows.

6. Plying apparatus comprising a rotatably driven member adapted to drive a first strand in a balloon about a second strand and a source of supply for said second strand, a second member freely rotatably mounted in spaced apart substantially axial alignment with said driven member and adapted to be rotatably driven about the axis of said balloon solely through the rotating engagement of said strand balloon therewith preceding the plying of said first strand with said second strand, and a first strand tensioning device disposed on and rotatable with said first rotatably driven member, said first strand tensioning device comprising a yarn storage variable wrap angle tension device including interconnected axial and transverse bores in said rotatably driven member and a peripheral strand engaging surface on said rotatably driven member adjacent said transverse bore.

7. Apparatus according to claim 6 wherein said second freely rotatable member has a guide member thereon and rotatable therewith engageable in rotatably driven relation by said first strand balloon, said freely rotatable solely-strand-driven member having a second strand tension device thereon and rotatable therewith, said second tension device being adapted to contact and tension said second strand.

8. Apparatus according to claim 7 further including third strand tensioning means disposed on said freely rotatable solely-strand-driven member and adapted to contact and tension said first strand.

9. Apparatus according to claim 8 wherein said second and third strand tensioning means are interacting and self-balancing in their tensioning action upon said first and second strand, the tensioning action of said second strand tensioning means being responsive to the differential tension in said first and second strands as it proceeds from said second and third tension device, the tensioning action of said third strand tensioning means being responsive to the differential tension in said first and second strands as it proceeds from said second and third tension devices.

10. Apparatus according to claim 9 wherein said second and third strand tension devices each function on the principle of variable sliding surface contact by said yarn, said sliding surface contact varying in response to the differential tension in said first and second strand as they proceed from said second and third tensioning means.

11. Apparatus according to claim 10 wherein the output tensions of each of said first and second strands as they proceed from said second and third tensioning means are opposed to one another, the extent of surface contact of each of said first and second strands with said third and second tensioning means respectively being a function of the differential tension between said opposed output tensions in said first and second strands.

12. Plying apparatus comprising a rotatably driven member adapted to drive a first strand in a balloon about a second strand and a source of supply for said second strand, a second member freely rotatably mounted in spaced apart substantially axial alignment with said driven member and adapted to be rotatably driven about the axis of said balloon solely through the rotating engagement of said strand balloon therewith preceding the plying of said first strand with said second strand, and a strand tensioning means disposed on said second freely rotatable solely-strand-driven member and adapted to tension said second strand.

13. Plying apparatus comprising a rotatably driven member adapted to drive a first strand in a balloon about a second strand and a source of supply for said second strand, a second member freely rotatably mounted in spaced apart substantially axial alignment with said driven member and adapted to be rotatably driven about the axis of said balloon solely through the rotating engagement of said strand balloon therewith preceding the plying of said first strand with said second strand, and tension balancing means on said freely rotatable solely-strand-driven member and adapted to contact and tension each of said first and second strands.

14. Plying apparatus comprising a rotatably driven member adapted to drive a first strand in a balloon about a second strand and a source of supply for said second strand, a second member freely rotatably mounted in spaced apart substantially axial alignment with said driven member and adapted to be rotatably driven about the axis of said balloon solely through the rotating engagement of said strand balloon therewith preceding the plying of said first strand with said second strand, and tension balancing means on said freely rotatable solely-strand-driven member and adapted to contact and tension each of said first and second strand, said tension balancing means including a surface for variable sliding surface contact by each of said first and second strands, the degree of said sliding surface contact by each of said strands being proportional to the differential tension in said first and second strands as they proceed from said tension balancing means.

15. Plying apparatus comprising first and second strands and individual supply packages therefor, a first rotatably driven member adapted to drive said first strand in a balloon about the supply package for said second strand, means for rotating said rotatably driven member, a second freely rotatable member disposed at one end of said balloon and in spaced apart separate relation from said rotatably driven member, guide means on said freely rotatable

member and adapted to engage said first strand balloon for rotation of said freely rotatable member solely by the energy of rotation of said balloon about the axis of said balloon, and a strand tensioning device disposed on said strand-driven freely rotatable member and adapted to contact and tension at least one of said strands.

16. Plying apparatus comprising first and second strands and individual supply packages therefor, a first rotatably driven member adapted to drive said first strand in a balloon about the supply package for said second strand, means for rotating said rotatably driven member, a second freely rotatable member disposed at one end of said balloon and in spaced apart separate relation from said rotatably driven member, guide means on said freely rotatable member and adapted to engage said first strand balloon for rotation of said freely rotatable member solely by the energy of rotation of said balloon about the axis of said balloon, and a variable wrap angle strand tension device disposed on said rotatably driven member and adapted to contact and tension one of said strands.

17. Apparatus according to claim 16, further comprising a strand tension device on strand-driven freely rotatable member and adapted to contact and tension said second strand.

18. Plying apparatus comprising a rotatably driven member adapted to drive a first strand in a balloon about a second strand and a source of supply for said second strand, a second member freely rotatably mounted in

spaced apart substantially axial alignment with said driven member and adapted to be rotatably driven about the axis of said balloon solely through the rotating engagement of said strand balloon therewith preceding the plying of said first strand with said second strand, and a first strand tensioning device disposed on and rotatable with said first rotatably driven member, said first strand tensioning device comprising a yarn storage variable wrap angle tension device including a strand guiding bore in said rotatably driven member and a peripheral strand engaging surface on said driven member adjacent one end of said bore.
